(57) **CLAIM**

The ornamental design for a shoe, as shown and described.

DESCRIPTION

1. Shoe

1.1 is a rear view of a shoe showing my new design;

1.2 is a right side view thereof;

1.3 is a perspective view thereof;

1.4 is a left side view thereof;

1.5 is a bottom view thereof; and

1.6 is a front view thereof.

The broken line showing of a shoe is for the purpose of illustrating portions of the article and forms no part of the claim.
